[57] CLAIM

The ornamental design for a utility body, as shown and described.

DESCRIPTION

FIG. 1 is a perspective view of a utility body showing of my new design;

FIG. 2 is a rear end view thereof;

FIG. 3 is a top view thereof;

FIG. 4 is a front view therefor;

FIG. 5 is a crossectional view thereof;

FIG. 6 is a side view thereof; and,

FIG. 7 is a crossectional view of a utility body showing a second alternative embodiment of my design.

The side, perspective, rear end, top and front views of the second embodiment shown in FIG. 7 are the same as those shown in FIG. 1-6 respectively.
